UNITED STATES PATENT OFFICE.

CLARENCE M. KEMP, OF BALTIMORE, MARYLAND.

CARBURETER.

SPECIFICATION forming part of Letters Patent No. 692,860, dated February 11, 1902.

Application filed February 20, 1901. Serial No. 48,109. (No model.)

To all whom it may concern:

Be it known that I, CLARENCE M. KEMP, a citizen of the United States, residing at Baltimore, in the State of Maryland, have invented 5 new and useful Improvements in Carbureters, of which the following is a specification.

My invention relates to carbureters or machines for providing an illuminating or fuel gas by enriching air with the inflammable 10 elements of any suitable volatile hydrocarbon, such as gasoline.

The present apparatus has been designed by me with the object of providing a carbureting plant which is peculiarly adapted for 15 use in house-lighting and relates not only to the carbureting devices proper, but also to the operating means therefor.

In working out my invention I have borne in mind the necessity of providing such a construction as that the initial cost of manufacture shall be as small as is compatible with structural safety and efficient operation, and, furthermore, it has been my object to so combine the necessary elements which make up 25 the apparatus as to give a very compact construction and one which may be packed or crated for shipping in a comparatively small compass, this being a matter of considerable importance. Again, the construction of carbureter forming the subject-matter of this case is one which minimizes the cost and labor of installation and admits of such a disposition of the devices for carbureting the air relative to the building to be supplied as 30 will permit its installation in any place desired, as a special cellar or outhouse is not essential for the plant and the charging of the same with gasoline is, at the same time, removed from dangerous proximity to the 35 building to be lighted. The motor mechanism and the air-feeding devices, which are combined with the carbureting devices proper and which form important features of the invention, are simple in operation and 40 easily manipulated, requiring but little attention, after being once installed to keep them in proper condition to actuate the carbureter and supply air thereto.

In the drawings accompanying and forming 45 a part of this specification, Figure 1 is a sectional view, in a vertical plane, of the carbureter and its connected parts, together

with the motor mechanism, the latter being in elevation and being broken from and offset relative to the rest of the figure. Fig. 2 55 is an enlarged detail plan view of the motor and its connected parts, portions of the structure being in section to bring the relation of the parts out more clearly. Fig. 3 is a view on line 3 3 of Fig. 2 looking in the direction 60 of the arrow to show the pawl-and-ratchet connection between the motor and the power-transmitting shaft. Fig. 4 is a detail view of the dipping-wheel which supplies the carbureting device. Fig. 5 is a view in elevation 65 of the entire apparatus, illustrating the plant as installed in working position.

Referring to the drawings by numerals, like numerals indicating like parts in the several figures, 1 indicates a tank or reservoir, preferably cylindrical in cross-section, provided with end plates or caps 2 and having at its upper side an air-inlet 3. Secured to the tank and surrounding said inlet 3 is a casting 4, which is shown in the present instance as being inclined to the tank 1, and screw-threaded or otherwise secured in the upper end of said casting 4, which is hollow, is a pipe 5, of considerable diameter, for a reason which will presently appear, said pipe 70 5 being preferably lined with a non-conducting material 6 and rising in an inclined direction from the tank 1, which is to be buried in the ground, as shown, a suitable distance 75 above the top of the ground. The inclination of the pipe 5 is of advantage, as thereby the power-transmitting connections from the motor to the driven parts are simplified both 80 in the number of parts and operation, and, further, in that it provides for a wide separation of the tank 1, containing the gasoline, from the rest of the apparatus and allows the use of a long air-pipe without the necessity of burying the tank at an inconvenient depth in the ground. Said pipe 5 85 90 supports at its upper end a casting or head 6^a, preferably of two parts, which are bolted or otherwise suitably secured thereto, so as to insure a tight connection, a cap or plug 6^b closing the upper end of said pipe 5 and 95 forming a bearing for the power-transmitting shaft referred to hereinafter, said casting 6^a at the upper end of pipe 5 and the casting 3, above referred to, serving as bearings for 100

a power-transmitting shaft 7, which will be hereinafter more fully described. Entering said pipe 5 at a point near its top is an air-inlet pipe 8, of any suitable construction, 5 said pipe 8 having at its end a downwardly-turned intake-cone 9, fitted with a strainer 10 to guard against the introduction of foreign substances or accident to the apparatus by fire. I preferably truss or support the 10 pipe 5 by means of a rod 11, secured at one end to a clip or ring 12, encircling the pipe 5 near its upper end, the other end of said rod 11 being secured to the end of the tank opposite that from which the pipe 5 rises.

15 In one end of the tank 1 is a storage-compartment which, as shown, is composed of two sections 13 and 14, said compartment 13 being formed by the vertical and horizontal partitions 15 and 16, while the other compartment 14 is formed with a vertical wall 17 and an inclined wall 18, the compartments communicating with one another by means of a port 19 in wall 18, Fig. 1. These two compartments are designed to hold the hydrocarbon-supply, a combined filling and vent pipe 20 of any suitable construction being used. Said filling-pipe 20 preferably extends to a point near the bottom of the compartment 13, so as to permit a draining of the 30 supply of oil, if desired, by simply attaching a suction-pump to the top of the pipe 20, which, it will be understood, rises from the tank 1 to a point above the surface of the ground. The compartment 14 is provided 35 with a vent 21 near its top, so as to permit the escape of air from said compartment during filling, the air in compartment 13 escaping through the edges of its top, which is merely a cover and is not air-tight.

40 The compartment 13 has an outlet-port 22, which communicates with a well or dipping-compartment 23, formed by the vertical partition 15 and the inclined wall 18, said well forming the receptacle for the supply of hydrocarbon for immediate consumption, which 45 it is desirable to segregate from the main body of liquid in order to avoid as much as possible the agitation of a large body of volatile hydrocarbon, such agitation of a large body 50 of this liquid being objectionable for reasons which will appear hereinafter.

At the other end of tank 1 is mounted a meter-wheel air-pump 24, of ordinary construction, said pump having air-trapping 55 members or arms and having its interior fitted with capillary materials, which constantly revolve in the gasoline, are kept saturated, and the gasoline is thereby evaporated and carried off by the air passing through the same, 60 the carbureted air being delivered to the central bore of the wheel and thence to a compartment 25 at the end thereof, into which compartment projects an outlet-pipe 26 for the gas, said outlet-pipe 26 having an upwardly-turned inner end to carry it above the level of the oil in the tank and passing through the end of the tank 1, so as to connect with a

stand-pipe 27, from which the distributing-pipe 28 leads. The said stand-pipe has a portion 29 depending below the points of connection of pipes 26 and 28, which is intended to serve as a trap for matters of condensation, and the trap portion 29 may be readily cleaned by attaching a suction-pump to the top of stand-pipe 27, which, as shown, projects 70 above the surface of the ground. The said meter-wheel pump 24 is carried by a shaft 30, which is mounted at one end in a bearing 31, formed at the angle or knee of outlet-pipe 26, (see Fig. 1,) said bearing being preferably a 80 roller-bearing to lessen friction. The other end of shaft 30 is supported in a bearing 32, carried by the vertical wall 18, said bearing being preferably a roller-bearing similar to 85 31. It will be seen that the bearings 31 32 of the meter-wheel shaft are both located inside of the tank and that there is no danger of leakage of gasoline or the volatile gases thereof through the bearings, as is apt to be the case where shafts or other moving parts pierce 90 the walls of the carbureting-tank. Said shaft 30 carries at its inner end one member of the knuckle-joint 33, the other member of said joint being mounted on the lower end of the power-transmitting shaft 7, to which reference 95 has been made, and while I find this knuckle-joint construction admirably suited for the purpose it will be understood that equivalent transmission devices, such as bevel-gears, may be used, if desired. Secured to said power-transmitting shaft 7 near its lower end and within the tank 1 is a dip-wheel 34, which owing to the inclined position of shaft 7 rotates in an inclined plane substantially parallel to inclined wall 18, so that its rim on its upper 105 side overhangs the vertical wall 17. As the said wheel 34 rotates the rim on the lower side of the wheel dips into the well or dipping-compartment 23, which, as has been stated, contains the small body of hydrocarbon for immediate consumption, and by means of dipping cups or buckets 35, secured to the rim of the wheel 34, the liquid is dipped from the well 23 and delivered to the meter-wheel compartment as the dipping-wheel 34 rotates. 110 The particular style of dipping wheel and buckets is not material, as this construction may be varied, if desired, without departing 115 from the spirit of my invention. In fact, any suitable device may be used for lifting the oil from the dipping-well and delivering it to the meter-wheel compartment. It will be apparent that as the meter-wheel is rotated through power-transmitting shaft 7, whose motor connections will presently be described, 120 it will draw in air through the air-inlet pipe 5, which air will pass to the outlet-pipe 26 at the end of tank 1 after being trapped and enriched in the ordinary manner by the meter-wheel. It is desirable that the air thus 125 drawn in be enriched for the most part in the carbureting-chamber and be not charged with the enriching elements before reaching the said chamber, as would be the case if the 130

air passed over a considerable area of hydro-carbon which was being agitated, and for this reason the storing of the bulk of the hydro-carbon-supply in the closed compartments 13 and 14 and the provision of the well or dipping-compartment 23 between the two is important, since by this construction a comparatively small body of liquid is exposed and agitated and the volatilization is therefore slight. The dipping-wheel 34 is dished, as shown, in order that it may reach low enough into the well 23 to dip gasoline therefrom at a low point and, furthermore, accommodate a trough or oil-chamber 36, which projects from said partition 17 and forms an extension of the pumping-wheel compartment, and being in communication with the said pumping-wheel compartment is always filled to the same level, so that the bearing 32 is well lubricated, the knuckle-joint 33 rotates in oil, and the necessity of a stuffing-box for the shaft which transmits power to the pumping-wheel is done away with.

As it is sometimes found desirable to drain the meter-wheel compartment, I provide a drain-pipe 37, which passes downward from the bottom of tank 1 and, turning upwardly, rises above the surface of the ground in convenient position for the application of a pump.

The power-transmitting shaft 7 traverses the air-pipe 5 centrally, a bearing bridge or spider 37^a being provided in casting 4 to carry and steady the lower part of said shaft, its upper end having its bearing in a cap in the upper end of pipe 3. Said power-transmitting shaft 7 is preferably a torsional shaft, and I have found a convenient way of making it is to form its removable middle portion 38 of a slender piece of steel, which is round or rectangular in cross-section and which is secured at each end to the end portions of the shaft. The object of providing a torsional shaft is that when the motor is running and the meter-wheel is being driven by the power-transmitting shaft said torsional portion 38 will be put under torsion, and if for any reason the motor is momentarily stopped—as, for example, during rewinding (a weight-motor being shown in the present case)—the power stored in the torsional shaft will be used in driving the meter-wheel and there will be no cessation of rotation of the latter. Furthermore, upon starting the machine the yielding action of the torsional shaft relieves the apparatus of the strain incident to overcoming the inertia of the meter-wheel immersed in a body of liquid and an easy starting results. It will be understood that, if desired, a torsional coil-spring may be substituted for the part 38, or the entire shaft may be of torsional material, and these equivalent constructions I consider to be within the range of my invention. The said power-transmitting shaft 7 is connected at its upper end by suitable transmitting connections, as knuckle-joint 39, with a two-part motor or power-shaft mounted in a frame 40, provided with

suitable bearings 41. I preferably form said frame 40 integral with one-half of the head 6, as shown in Fig. 2, as this gives a very strong compact arrangement of parts, the upper end of air-pipe 5 acting as a support for one end of said frame 40, the other end of the frame being supported by suitable standards 42. The two members 43 44 of the two-part driving-shaft are connected by a ratchet-and-pawl connection, the ratchet member 45 being mounted in the present instance on a hub or pinion 46, keyed to the shaft member 43, and the pawl 47 being carried by a large ratchet-wheel 48 on the abutting end of shaft member 44, so that the two shaft members 43 44 are locked together when the rotation is in one direction, but when in the other turn independently with the pawl 47 trailing idly. The shaft 44 is locked against movement in one direction by means of a pawl 49, pivoted to the frame 40 and engaging the ratchet 48, above referred to, thus preventing the torsional power-transmitting shaft from driving the shaft member 44 backward when the parts 43 and 44 are disconnected. Mounted on the said shaft member 43 is a circumferentially-grooved winding-drum 51 of the ordinary type, which is preferably mounted on roller-bearings 52 and free to turn on said shaft 43. Said drum has secured thereto or formed integral therewith a gear-wheel 53, which engages a pinion 54 of a back-gear 55, mounted on roller-bearings on a stud-shaft 56 on the frame, said back-gearing meshing with the pinion 46 on shaft member 43, so as to drive the latter in one direction when the weight 57 is wound up, and through the pawl-and-ratchet connection above referred to the shaft 44 and through it and the power-transmitting shaft 7 drive the dip-wheel 34 and meter-wheel 24.

When the weight 57 has run down and it becomes necessary to rewind the weight-carrying rope on drum 51, a crank or other device is applied to the squared end of the shaft 43. Rotation of the shaft 43 will drive the pinion 46, the pawl 47 trailing idly over ratchet 45, so that no motion is imparted to shaft 44, said shaft 44 being held against backward movement by pawl 49. The rotation of pinion 46 is communicated to back-gear 55 and in turn to the winding-drum 51 through pinion 54 and gear 53 and the weight 57 is drawn up. If desired or necessary, a hole 58 may be made in the ground to receive weight 57, and the rope may be run over a system of pulleys in passing to the drum.

It is sometimes found desirable to warm the air before it passes to the carbureting devices, and for this purpose I provide a pipe 59, running from the stand-pipe 27 and having a burner 60 beneath the air-inlet pipe 8, so that by lighting the burner 60 the air may be heated, and since the pipe 5 is lined with non-conducting material, as hereinbefore stated, the air will retain the heat until it reaches the carbureting-tank 1.

I do not wish to be understood as confining my invention to the particular details and features of construction herein shown and described, as I have set forth merely one embodiment of my invention, and it is apparent that the structural features may be varied within the skill of the mechanician without departing from the range of my invention. For instance, I have herein shown and described 5 the pipe 5 through which the power-transmitting shaft passes as being inclined; but I do not desire to be understood as limiting myself to such an arrangement of this pipe, for obviously the same may be placed vertically. Having this modification in mind, therefore, I have in some of the claims specified the pipe 5 as "leading upward" from the tank. Neither do I wish to be understood as limiting myself to the precise construction 10 of the air-feed pipe 8 communicating with the pipe 5, for it will be obvious that this pipe 8 may lead directly to the tank, or it may be dispensed with entirely, in which case the air would be supplied to the tank through the 15 combined filling and vent tube, the cap 20 being left off for the entrance of the air.

In some cases, as where a very cheap apparatus is desirable, I contemplate dispensing with the dipping-wheel and separate oil-storage compartment and employing only the air-pumping wheel and driving connections, traversing the upwardly-extending pipe 5, as before set forth, and I desire it to be understood that my invention contemplates such a construction of apparatus.

I claim—

1. In a carbureter, the combination with a tank adapted to hold a body of hydrocarbon, of an air-pumping wheel rotatably mounted 30 in said tank and immersed in the body of hydrocarbon, an air-supply pipe leading from said tank, means for driving said pumping-wheel, whereby air is drawn into the tank and converted into gas through its contact with the hydrocarbon and power-transmitting connections traversing said air-pipe.

2. In a carbureter, the combination with a tank having an air-pumping-wheel compartment at one end, of an air-pumping wheel rotatably mounted therein, means for supplying hydrocarbon to said wheel-compartment, an air-supply pipe leading from said tank, means for driving said air-pumping wheel, whereby air is drawn into the tank and converted into gas by being brought into contact with the hydrocarbon, and interconnecting power-transmitting devices traversing said air-pipe.

3. In a carbureter, the combination with a tank having an air-pumping-wheel compartment at one end, of an air-pumping wheel rotatably mounted therein, means for supplying hydrocarbon to said wheel-compartment, an inclined air-supply pipe leading from said tank, means for driving said air-pumping wheel, whereby air is drawn into the tank and converted into gas, and interconnecting

power-transmitting devices traversing said inclined air-pipe.

4. In a carbureter, the combination with a tank having an air-pumping-wheel compartment at one end, of an air-pumping wheel rotatably mounted therein, a hydrocarbon-supply compartment at the other end of said tank, means for feeding the hydrocarbon from said supply-compartment to said pumping-wheel compartment, an air-supply pipe leading from said tank, means for driving said pumping-wheel, and interconnecting power-transmitting devices traversing said air-pipe. 70 75 80

5. In a carbureter, the combination with a tank having a wheel-compartment at one end, of an air-pumping wheel rotatably mounted therein, a closed compartment at the other end of said tank to contain a supply of hydrocarbon, an open well or reservoir communicating with said supply-compartment, means for transferring hydrocarbon from said well to said pumping-wheel compartment, an air-supply pipe leading from said tank, driving means for said pumping-wheel, and interconnecting power-transmitting devices traversing said air-pipe. 85 90 95

6. In a carbureter, the combination with a tank having a wheel-compartment at one end, of an air-pumping wheel rotatably mounted therein, a closed compartment at the other end of said tank to contain a supply of hydrocarbon, an open well or reservoir communicating with said supply-compartment, a dipping-wheel for transferring hydrocarbon from said well to said pumping-wheel compartment, an air-supply pipe leading from said tank, driving means for said pumping-wheel, and interconnecting power-transmitting devices traversing said air-pipe. 100 105

7. In a carbureter, the combination with a tank having a compartment at one end, of an air-pumping wheel rotatably mounted therein and having a suitable outlet, a supply-reservoir for hydrocarbon, a dipping-wheel mounted so as to rotate in said reservoir in an inclined plane and overhang said pumping-wheel compartment, means for driving said dipping-wheel, means for driving said pumping-wheel, and an air-supply pipe leading from said tank. 110 115

8. In a carbureter, the combination with a tank having a compartment at one end, an air-pumping wheel rotatably mounted in said compartment, a closed compartment at the other end of said tank for the supply of hydrocarbon, a well in communication with said supply-compartment, an inclined dipping-wheel running in said well and overhanging said wheel-compartment, means for driving said pumping-wheel, said means serving also to rotate said dipping-wheel, and an air-supply pipe leading from said tank. 120 125

9. In a carbureter, the combination with a tank having a compartment in one end, of an air-pumping wheel rotatably mounted therein and provided with a suitable outlet, a closed compartment at the other end of said

- 5 tank to hold the supply of hydrocarbon, an open well in communication with said supply-compartment, an air-supply pipe leading from said tank, a power-transmitting shaft traversing said air-pipe and connected with said pumping-wheel, and an inclined dipping-wheel mounted on said shaft, said dipping-wheel running in said open well and overhanging said pumping-wheel compartment.
- 10 10. In a carbureter, the combination with a tank having a compartment in one end, of an air-pumping wheel rotatably mounted therein and provided with a suitable outlet, a closed compartment at the other end of said tank to hold the supply of hydrocarbon, an open well in communication with said supply-compartment, an inclined air-supply pipe leading from said tank, an inclined power-transmitting shaft traversing said inclined air-pipe and connected with said pumping-wheel, and a dipping-wheel mounted on said inclined shaft, said dipping-wheel running in said open well and overhanging said pumping-wheel compartment.
- 15 11. In a carbureter, the combination with a tank having a compartment at one end, of an air-pumping wheel rotatably mounted therein, a closed double compartment at the other end of said tank for the supply of hydrocarbon, a well intermediate the sections of said supply-compartment and in communication therewith, an inclined air-supply pipe leading from said tank, a power-transmitting shaft traversing said inclined air-pipe and connected with said wheel, means for driving said shaft, and a dipping-wheel mounted on said shaft and running in said intermediate well and overhanging said pumping-wheel compartment.
- 20 12. In a carbureter, the combination with a tank having a compartment at one end, of an air-pumping wheel rotatably mounted in said compartment, a closed compartment at the other end of said tank to hold the hydrocarbon-supply, a well between the said compartments and in communication with said supply-compartment, an air-supply pipe, means for driving said pumping-wheel, a power-transmitting shaft traversing said air-supply pipe and having a driving connection with the pumping-wheel shaft, a trough projecting from the wall of said pumping-wheel compartment and in communication therewith in which the said driving connection turns, and a dipping-wheel mounted on said power-transmitting shaft and running in said well, said dipping-wheel being inclined so as to overhang the pumping-wheel compartment, and being dished to accommodate said projecting trough.
- 25 13. In a carbureter, the combination with a tank having an air-supply pipe and a gas-outlet pipe, of a vertically-placed partition substantially midway said tank to form separate compartments therein, a journal-bearing carried by said partition, a journal-bearing at the inner end of said outlet-pipe, an air-pumping wheel rotatably mounted in said bearings, means for driving said pumping-wheel, a power-transmitting shaft traversing said air-pipe and having a driving connection with said pumping-wheel, a closed compartment to receive the main supply of hydrocarbon, an open compartment or well in communication with said closed compartment, a dipping-wheel carried by said power-transmitting shaft running in said well, said dipping-wheel being inclined so as to overhang the said vertical partition and being provided with buckets to deliver hydrocarbon from said well to the pumping-wheel compartment.
- 30 14. In a carbureter, the combination with a tank having a suitable air-inlet and a gas-outlet, of an air-pumping wheel rotatably mounted in said tank, means for supplying a body of hydrocarbon in which said pumping-wheel runs, and a torsional power-transmitting shaft connected with said pumping-wheel, and operating to rotate the wheel whereby air is drawn into the tank and converted into gas.
- 35 15. In a carbureter, the combination with a tank having an air-pumping wheel rotatably mounted therein, of means for supplying a body of hydrocarbon in which said pumping-wheel runs, an air-pipe leading from said tank, a power-transmitting shaft traversing said air-pipe and having a driving connection with said pumping-wheel shaft, whereby the wheel is rotated to draw air into the tank and convert it into gas, a bearing at the lower end of said air-pipe for said power-transmitting shaft, a head or cap closing the upper end of said air-pipe and forming the upper bearing for said transmitting-shaft, an air-feeding pipe entering said air-supply pipe and a motor-shaft connected with the upper end of said power-transmitting shaft.
- 40 16. In a carbureter, the combination with a tank having an air-pumping wheel rotatably mounted therein, and constructed to draw air into the tank and convert it into gas, of means for supplying a body of hydrocarbon in which said pumping-wheel runs, an inclined air-pipe leading upward from said tank, a torsional power-transmitting shaft traversing said air-pipe, and having a knuckle-joint driving connection with said pumping-wheel shaft, a bearing at the lower end of said inclined air-pipe for said power-transmitting shaft, a head or cap closing the upper end of said air-pipe and forming the upper bearing for said torsional transmitting-shaft, an air-feeding pipe entering said air-supply pipe, and a motor-shaft connected with the upper end of said power-transmitting shaft.
- 45 17. In a carbureter, the combination with a tank adapted to be buried in the ground and having an air-pumping wheel and a supply-compartment for hydrocarbon therein, of means for delivering hydrocarbon from said supply-compartment to the pumping-wheel, an inclined air-supply pipe leading from said

5 tank, said pipe being provided with heat-non-conducting material and being closed at its top, an air-inlet pipe entering said supply-pipe, means for heating said inlet-pipe, a motor for driving the air-pumping wheel, and a power-transmitting shaft traversing said air-supply pipe.

18. In a carbureting apparatus, the combination with a tank adapted to be buried in 10 the ground, of air-carbureting means located within said tank, an air-shaft pipe leading upward from said tank, means for driving the air-carbureting means and a power-transmitting shaft traversing and having its bearing 15 in said air-supply pipe.

19. In a carbureting apparatus, the combination with a tank adapted to be buried in the ground, of air-carbureting means located within said tank, an inclined air-supply pipe 20 leading upward from said tank, means for driving the air-carbureting means, and a torsional power-transmitting shaft traversing and having its bearings in said air-supply pipe.

20. In a carbureting apparatus, the combination with a tank adapted to be buried in the ground and provided with air-carbureting devices, of an inclined air-supply pipe leading upward from said tank, shaft-bearings at 25 either end of said pipe, a power-transmitting shaft mounted in said bearings and having an intermediate torsional part, a motor-shaft connected with said torsional power-transmitting shaft, means for preventing backward rotation of said motor-shaft, and driving connections between said power-transmitting shaft and said air-carbureting devices.

21. In combination, a carbureting - tank 40 having air - carbureting instrumentalities therein, an air-supply pipe leading from said tank, a power-transmitting shaft traversing said air-supply pipe, driving connections between said shaft and said air-carbureting instrumentalities, and a motor-shaft connected with said power-transmitting shaft.

22. In combination, a carbureting - tank having air - carbureting instrumentalities therein, an air-supply pipe leading upward 50 from said tank, a torsional power-transmitting shaft traversing said air-supply pipe, driving connections between said shaft and said air-carbureting instrumentalities, a motor-shaft connected with said power-transmitting shaft, and means for preventing 55 backward movement of said power-transmitting shaft.

23. In combination, a carbureting - tank having air - carbureting instrumentalities 60 therein, an air-supply pipe leading from said tank, a torsional power - transmitting shaft mounted in and traversing said air-supply pipe, driving connections between said shaft and said air-carbureting instrumentalities, a 65 motor-shaft, pawl-and-ratchet connections between said motor-shaft and said power-trans-

mitting shaft, a pawl-and-ratchet locking device to prevent backward rotation of said power-transmitting shaft, a winding - drum loosely mounted on said motor-shaft, a gear-wheel carried by said drum, back gearing driven by said gear-wheel, and a pinion keyed to said motor-shaft and meshing with said back gearing.

24. In combination, a carbureting - tank 75 having air - carbureting instrumentalities therein, an air-supply pipe leading from said tank, a power-transmitting shaft mounted in and traversing said air-supply pipe, said shaft having a driving connection with said air-carbureting instrumentalities, means for driving said power-transmitting shaft comprising two shafts one of which is connected with said power-transmitting shaft, a ratchet-and-pawl connection between the said first shaft and 80 the other, a pinion keyed to the second shaft, back gearing meshing with said pinion, a winding-drum loosely mounted on said second shaft, a gear-wheel secured to said winding-drum, and meshing with said back gearing, and a weight to rotate said winding-drum.

25. In a carbureter, the combination with an tank having a compartment in one end, of an air-pumping wheel rotatably mounted in 95 said compartment, an outlet - pipe entering said air-pumping-wheel compartment, a stand-pipe with which said outlet - pipe connects having a depending trap portion, a drainage-pipe for said pumping-wheel compartment, a 100 closed hydrocarbon-supply compartment in the other end of said tank, a filling and vent pipe therefor, said pipe serving also as a drainage-tube, a well or reservoir in communication with said supply-compartment, an 105 air-supply pipe entering said tank, a power-transmitting shaft mounted in and traversing said air-supply pipe, driving connections between said shaft and said pumping-wheel, an inclined dipping-wheel carried by said power-transmitting shaft, said dipping-wheel running in said well and overhanging said pumping-wheel compartment, and a motor connected with and driving said power-transmitting shaft.

26. In a carbureting apparatus, the combination with a tank, of air-carbureting instrumentalities therein, an air-supply pipe leading upward from said tank, a power-transmitting shaft traversing said air-pipe and having a driving connection with said air-carbureting instrumentalities, said shaft comprising a member mounted in bearings at the lower end of said air-supply pipe, a second member mounted in bearings at the upper 120 end of said pipe, and an intermediate section removably attached to said members, and a motor connected with said power-transmitting shaft.

27. In a carbureting apparatus, the combination with a tank, of air-carbureting instrumentalities therein, an inclined air-supply

pipe leading from said tank, a power-transmitting shaft traversing said air-pipe and having a driving connection with said air-carbureting instrumentalities, said shaft comprising a member mounted in bearings at the lower end of said air-supply pipe, a second member mounted in bearings at the upper end of said pipe, and an intermediate torsional section removably attached to said members, and a motor connected with said power-transmitting shaft.

28. In a carbureter, the combination with a tank containing the air-carbureting instrumentalities, of means for driving said instrumentalities, and a power-transmitting shaft comprising two end members mounted in suitable bearings and a removable, intermediate section, connecting said driving means and said air-carbureting instrumentalities.

29. In a carbureter, the combination with a tank containing the air-carbureting instrumentalities, of means for driving said instrumentalities, and a power-transmitting shaft comprising two end members mounted in suitable bearings and a removable torsional, intermediate section, connecting said driving means and said air-carbureting instrumentalities.

30. In a carbureter, the combination with a tank having an air-supply pipe and a gas-outlet pipe, of a vertically-placed partition substantially midway said tank to form separate compartments therein, a journal-bearing carried by said partition, a journal-bearing at the inner end of said outlet-pipe, an air-pumping wheel rotatably mounted in said bearings, means for driving said pumping-wheel, and a power-transmitting shaft traversing said air-pipe and having a driving connection with said pumping-wheel.

31. In a carbureter, the combination with a tank adapted to hold a body of hydrocarbon, of an air-pumping wheel rotatably mounted in said tank and immersed in the body of hydrocarbon, a pipe leading upward from said tank, means for driving said pumping-wheel, whereby air is drawn into the tank and converted into gas, power-transmitting connections traversing said pipe, and an air-inlet and a gas-outlet for the tank.

32. In a carbureting apparatus, the combination with a tank adapted to be buried in the ground, of air-carbureting means located within said tank, a pipe leading upward from said tank, means for driving the air-carbureting means whereby the air drawn within the tank is converted into gas, a power-transmit-

ting shaft traversing said pipe, and an air-inlet and gas-outlet for the tank.

33. In a carbureting apparatus, the combination with a tank buried in the ground and adapted to hold a body of hydrocarbon, of an air-pumping wheel rotatably mounted in said tank and immersed in the body of hydrocarbon, a pipe leading upward from said tank, a power-transmitting shaft traversing said pipe, means for rotating said shaft, whereby the pumping-wheel is rotated and air drawn into the tank and in contact with the hydrocarbon to convert said air into gas, and an air-inlet and a gas-outlet for the tank.

34. In a carbureting apparatus, the combination with a tank buried under ground and adapted to hold a body of hydrocarbon, of an air-pumping wheel rotatably mounted in the tank and having its bearings wholly within the same whereby the use of stuffing-boxes in the ends of the tank is avoided, a pipe leading upward from the tank and terminating above the ground, a power-transmitting shaft for driving the pumping-wheel, traversing said pipe, means for driving said shaft, whereby the pumping-wheel is rotated to draw air into the tank to convert it into gas, and an air-inlet and a gas-outlet for the tank.

35. In a carbureter, the combination with a tank buried in the ground and adapted to hold a body of hydrocarbon, of air-carbureting instrumentalities located in said tank and immersed in the body of hydrocarbon therein, a pipe leading upward from said tank and terminating above the surface of the ground and power-transmitting means for driving the air-carbureting instrumentalities traversing said pipe.

36. In a carbureter, the combination with a tank adapted to hold a body of hydrocarbon, of an air-pumping wheel rotatably mounted in said tank and immersed in the body of hydrocarbon therein, a pipe leading upward from said tank, means for driving said pumping-wheel whereby air is trapped by the wheel and brought into contact with the hydrocarbon and converted into gas, power-transmitting connections traversing said pipe, and an air-inlet and a gas-outlet for the tank.

In testimony whereof I have hereunto set my hand in presence of two subscribing witnesses.

CLARENCE M. KEMP.

Witnesses:

MARY MOWAN,
NANNIE WELLER.
